UNITED STATES PATENT OFFICE.

FRANK V. MURPHY, OF BAY CITY, MICHIGAN.

SHOE-SHINING MACHINE.

1,128,894.

Specification of Letters Patent.

Patented Feb. 16, 1915.

Application filed April 18, 1914. Serial No. 832,768.

To all whom it may concern:

Be it known that I, FRANK V. MURPHY, a citizen of the United States, and a resident of Bay City, in the county of Bay and State 5 of Michigan, have made certain new and useful Improvements in Shoe-Shining Machines, of which the following is a specification.

My invention is an improvement in shoe 10 shining machines, and has for its object to provide a coin controlled machine of the character specified, for polishing shoes, either black or tan, and wherein mechanism is provided for polishing the shoes, 15 adapted to properly polish shoes of varying sizes, and wherein the mechanism is so arranged, that by inserting a coin of the proper denomination the polishing mechanism will be set in operation.

20 In the drawings: Figure 1 is a side view of the improved machine with a part in section, Figs. 2 and 4 are sections on the line 2—2 and 4—4, respectively, of Fig. 3, looking in the direction of the arrows, Fig. 3 is a 25 top plan view, Fig. 5 is a transverse vertical section showing the carriage in inoperative position, Fig. 6 is a section on the line 6—6 of Fig. 5, Fig. 7 is a perspective view of one 30 of the polishing elements, and Fig. 8 is a section on the line 8—8 of Fig. 3.

The present embodiment of the invention 35 comprises a base 1 of suitable size which is provided at each side edge with an overlying flange 2, the said flanges being spaced above the upper face of the base, as shown. A casing or cabinet 3 is supported on one 40 end of the base, and the said casing or cabinet is provided with a seat 4 intermediate its ends, for the use of the person desirous to be operated upon.

The seat, as shown, is provided with arm 45 rests 5, and a back 6, and foot plates 7 are connected to a rod 8 which is supported by the cabinet below and in front of the seat. Each of the foot rests is connected with the 50 return portion 9 of a bracket 10, and each bracket is provided with a lateral lug 11 intermediate its ends, and each lug has a bearing 12, which engages the rod 8, before mentioned.

The rod extends transversely of the seat, and the upper end of each bracket 10 is provided with a resilient leg clasp or clip 13, for engaging the leg of the person operated 55 upon. This clip or clasp 13 is provided with

a depending shield 14, for protecting the trousers, and the clip or clasp is in the form of a split ring, the opening of the ring being at the front so that it may be easily engaged with the leg.

A carriage 15 is mounted to move on the base, the carriage having at each side edge downwardly offset and outwardly extending journal pins 16, upon which are journaled 60 wheels 17, and the wheels engage the upper face of the base beneath the flanges 2, the said flanges acting as retainers to prevent upward movement of the wheels and the carriage. The carriage 15 supports the polishing mechanism. The polishing mechanism 65 comprises a series of pairs of brushes 18 for each shoe, and each brush is secured to a plate 19, having a central lug 20, which is pivoted to a lateral lug 21 at the upper end of one of the sections 22 of a sectional 70 arm 22—22^a. The sections of the arms are spaced apart longitudinally with respect to each other, and a coil spring 23 is provided for connecting the sections.

The ends of the spring are secured to the 75 sections by means of eyes or staples 24. The brush is thus mounted resiliently, and the section 22^a of the arm is provided with a socket at its lower end for engaging an 80 standing lug 25 on one of the links of a chain or other flexible member 26. As before stated, a series of pairs of brushes is 85 provided for each shoe, and the brushes are mounted in such manner, that when the carriage 15 is moved toward and from the seat 90 or cabinet 3, the brushes of each series will engage the adjacent shoe to polish the same.

A pair of upper shafts 27 is arranged parallel and in spaced relation adjacent to each shoe, the said shafts being journaled on 95 standards 28, and a pair of lower shafts 29 is journaled on the standards below the shafts 27. The standards 28 of each pair of upper and lower shafts are arranged in alignment transverse to the carriage, so that 100 the shafts are supported in parallelism with the long axis of the foot rest.

Sprocket wheels 30 and 31 are secured to the shafts 27 and 29, and one of the chains 105 26 is supported on each registering pair of sprocket wheels 30—31. The sprocket wheels 30 of shafts 27 are arranged directly above and in register with the sprocket wheels 31 of the adjacent shafts 29, and two of the brushes 18 are connected 110

with each chain, the said brushes being directly opposite each other. Other brushes 32 are connected with the standards 28 adjacent to the foot rest, each brush being secured to a sectional arm, having a spring 33 interposed between the sections.

- One of the sections 34 of the arm is connected to a standard, and the other section 34^a of the arm is connected to the brush.
- 10 The arms 34—34^a of the two brushes adjacent to each foot rest are in alinement, and the bristles of the brushes are spaced apart a distance to permit the passage of the shoe and the foot plate between the brushes. A 15 pulley 35 is secured to each of the shafts 27 at approximately the center thereof, and each pulley is connected to a pulley 36 on the shaft 29 immediately below, by means of a belt 37.
- 20 A sprocket wheel 38 is secured to the inner end of each shaft 29, and the sprocket wheels of the four shafts 29 are engaged by a chain 39, which also passes over a sprocket wheel 40 on the shaft 41 of a motor 42 25 which is supported on the carriage 15. The motor in the present instance is an electric motor, and is connected with the carriage near one end and adjacent to the cabinet 3. The chain 39 thus drives the four shafts 29, 30 and in addition to the four sprocket wheels 38 on the sprocket wheel 40 the chain 39 passes over a sprocket wheel 43 journaled on a stub shaft 44 supported by a bracket arm 45 extending laterally from the standards 28, at the end of the carriage remote 35 from the motor. The sprocket wheel 43 is in alinement with the sprocket wheels 38, and the chain passes over another sprocket wheel 46 journaled on a stub shaft 47 extending inwardly from the center of the carriage 15.

It will be noted from an inspection of Fig. 3, that the four shafts 27 and 29 adjacent to each foot rest carry seven pairs of 45 chains 26, and since each chain carries two brushes, there are 28 brushes adjacent to each foot rest. The four shafts 29 are driven by the chain 39, and each shaft 29 drives a shaft 27.

- 50 It will be noted from an inspection of Fig. 5, that the front of the cabinet 3 is open, so that the carriage 15 may move into the position of Fig. 3, or in the position of Fig. 5. When in the position of Fig. 5 the polishing mechanism is within the cabinet. Each 55 of the sprocket wheels 30 on the shafts 27, and each of the sprocket wheels 31 on the shafts 29 is secured to a hub or sleeve, and the sprocket wheels of each shaft are arranged in pairs, excepting that wheel of each shaft adjacent to the foot rest when the carriage is in the position of Fig. 3.

Four sprocket wheels of each shaft are on one side of the pulleys 35 and 36 before 60 mentioned, and three sprocket wheels of

each shaft are on the opposite side. The four wheels of each shaft in front of the pulley 36 are secured to two sleeves, and that end of the innermost sleeve on the shaft 29 adjacent to the pulley 36 is provided with clutch or ratchet teeth. That end of the sleeve on the other side of the said pulley is also provided with ratchet teeth, and the teeth of each sleeve are adapted to co-operate with similar teeth on the sleeve 48 to 75 which the pulley 36 is secured.

A lever 49 is pivoted to a lug 50 on a bracket 51 which connects the two central rear standards 28, and the lever is connected to the sleeves 48 of all of the pulleys 36, by means of a rod 53 which passes through a slot 54 intermediate the ends of the lever, and angular arms 52—52^a connect the rod 53 with the several sleeves. The portion 52 of each arm extends forwardly 80 from the rod 53, and the portion 52^a of each of the arms engages an annular groove in the hub. The lever is provided with latch mechanism 55 for holding it in adjusted position, and it will be evident that when 85 the lever is moved in one direction, the sleeve 48 will be engaged with the sprocket wheels immediately in front of the same, while when the lever is moved in the opposite direction it will be engaged with the 90 sprocket wheels immediately behind the sleeve.

The link or rod 53 extends to the ends of the carriage, and at each end the said rod or link is provided with an arm 56 extending 100 parallel with the portions 52 of the arms 52—52^a. A rack bar 57 is provided at the outer end of each arm 55, and each rack bar engages a pinion 58 secured to a pulley 59 journaled on the body 60 of a U-shaped bracket, whose arms 60^a are connected with the adjacent standards 28.

Vats or tanks 61 and 61^a are arranged below the brushes, on the upper face of the carriage, the said vats extending longitudinally of the carriage at the center thereof, and each vat is provided at its sides with eyes 62 which engage guide standards or rods 63 arising from the top of the carriage for guiding the vats in their vertical movement. A flexible member, as for instance cord or wire 64 passes over each of the pulleys 59, and the ends of the flexible members are connected with the vats or tanks, in such manner that when the pulleys 59 are 115 rotated in either direction, one tank or vat will be lifted, and the other will be lowered. 120

The vat 61 is arranged directly below the two innermost brushes of the eight brushes directly in front of the pulleys 36 while the 125 vat 61^a is arranged directly below the eight brushes immediately in rear of the said pulleys, and the vats are in such position, that when lifted, as shown in Figs. 1 and 5, the brushes adjacent to the vat will dip into 130

the material therein. Each vat is divided into two compartments by a longitudinally extending partition 64, and liquid is to be placed in the forward compartment of each 5 vat, and paste in the rear compartment.

One of the vats is designed to contain material to polish black shoes while the other is designed to contain material to polish tan shoes. Four brushes will dip into 10 the liquid compartment and four into the paste compartment. The eight brushes at the front of the carriage and the four brushes at the rear of the carriage are polishing and cleaning brushes.

15 By means of the lever 49 the eight brushes immediately in front of the pulleys 36, or the eight brushes immediately in rear thereof may be connected with the motor. The four brushes at the rear of the carriage, and 20 the eight brushes at the front of the carriage, are always connected with the shafts. That is the sleeves of the eight front brushes and the sleeves of the four rear brushes are secured to the shaft. When the lever 49 is 25 operated to connect either set of the material applying brushes to the motor, the rack bars 57 operate the pulleys 59, to lift the proper tank into position to be engaged by the operating brushes, to receive polish therefrom.

30 It will be noted from an inspection of Figs. 1, 4 and 5 that a groove 65 is provided in the upper face of the base at the center thereof, and extending longitudinally of the base. The carriage is also provided with a 35 groove 66 in its under face registering with the groove 65. A rod 67 is arranged longitudinally of the groove 65, and a lever 68 is arranged at one end of the rod, the lever having a head at its upper end as 40 shown. The lever is also pivoted in the groove at its lower end, as shown at 69, and a series of teeth 70 is arranged in the groove in spaced relation with respect to each other, and with respect to the lever 68. Each tooth 45 is pivoted to the bottom of the groove and to the rod 67, and the teeth extend above the rod, as shown in Fig. 1.

The shaft 47 before mentioned, is provided with a worm wheel 71, and the said 50 wheel is adapted to engage the teeth, to propel the carriage toward and from the cabinet and chair. An inclined stop 72 is arranged at the front end of the rod, for engagement by the worm wheel 71, to limit 55 the movement of the carriage away from the seat. A fan 72 is secured to the hub of each pulley 35, and the fans are operated by the pulleys, which in turn are operated by the belts 37, which connect them with the 60 pulleys 36 on the shafts 29.

When not in use, the carriage with the 65 polishing mechanism is in the position shown in Figs. 5 and 6, that is beneath the cabinet. Coin controlled mechanism of any desired character may be used for releas-

ing the carriage and for starting the motor. This mechanism however forms no part of the invention, and for this reason is not shown nor described. The mechanism is, however, so arranged that when the proper 70 coin is inserted, the motor will be started, to operate the polishing mechanism. The person desiring his shoes polished seats himself and places his feet on the rests. The spring clips are designed to embrace the 75 lower leg, and curtains or shields 14 are designed to reach to the shoe tops, to protect the socks and the lower part of the trousers.

The carriage occupies the position shown 80 in Fig. 3, when the operation commences. As soon as the motor begins to run the carriage will begin to move toward the chair. The brushes 32 first engage the shoes at the sides, cleaning the soles and the heels, and 85 the depression between the sole and the upper. These brushes are yieldingly mounted, as are all the brushes, so that whether the shoe is large or small they will operate with equal efficiency. The first set of brushes at 90 each side, that is the rearmost brushes next engage the shoe thoroughly cleaning the same. The operator will move the lever 49, to connect the pulley 36 with the set of brushes adjacent to the character of polish 95 which he desires to use. Mechanism is also provided for permitting the user to move the carriage out from beneath the seat into position to commence polishing. The said mechanism comprises a shaft 75 which is 100 journaled in bearings 76 on a cross plate 77 arranged beneath the seat. The shaft is provided with a radial crank arm 78 at one end, the body of the arm extending upwardly through a chamber 79 in one of the arm 105 rests, while the handle of the crank extends through an arc-shaped slot 80 in the arm rest, into convenient position to be grasped by the operator. The shaft 75 is also provided with another radial arm 81 at the opposite end from the crank arm, and the arm extends forwardly and downwardly, and is connected to the lug 50 by means of a link 82. It will be evident that when the crank 110 arm is swung forwardly from the position shown in full lines in Fig. 8 to the position shown in dotted lines the carriage will be rolled out from beneath the cabinet, to a position where it will be ready to operate upon the shoes of the user.

The motor 42 is supplied with current by lead wires arranged within a cable 83, which extends from a switch 84 on the rear of the seat to the motor. The switch is opened and closed by means of a lever 85 115 which is pivoted at 86 in the chamber 79, and the crank arm 78 is provided with a rearwardly extending lug or arm 87 for engaging the switch lever when the arm is 120 swung rearwardly to swing the said lever 125 130

to close the switch, whereby to actuate the motor.

A second lever 88 is pivoted within the chamber at the opposite side from the lever 85, as indicated at 89, and a link 90 connects the lever 88 with the lever 85. When the crank arm 78 is swung forwardly by the carriage moving to position beneath the seat, the said crank arm will engage the lever 88, 10 and will swing the lever in a direction to cause the lever 85 to open the switch. It is obvious that any desired coin controlled mechanism might be provided for releasing the shaft 75 to permit the user to move the 15 carriage into operative position. The chute for the coin is shown in Fig. 3 at 91.

The operation of the improvement as a whole is as follows: When the parts are in the position of Fig. 5, the user seats himself, 20 inserts the proper coin, and the coin actuates the coin controlled mechanism to release the operating mechanism. The user now grasps the crank arm 78 which is at the front of the seat, and pulls the arm rearwardly, thus rolling the carriage into the 25 position of Fig. 1. As the carriage reaches this position, the crank arm 78 closes the switch, and the motor commences operation. The user should arrange his feet on the rest, 30 with the clips 13, and the shields 14 in proper position, before swinging the crank arm. As soon as the switch is closed, the lever starts, and the carriage begins to move back to its position beneath the seat. As soon as 35 the carriage has been moved into the position of Fig. 1, or before, the user places the lever 49 properly, to connect the proper applying brushes, and to move the proper tank into position for engagement by the 40 brushes. If he desires a tan polish he will move the lever into the position of Fig. 1, while if he desires a black polish, he will move the lever forwardly. Either vat of course may contain black and the other tan 45 polish, but in the present instance it is supposed that the vat 61 contains the materials for a black polish, while the vat 61^a contains the materials for a tan polish.

Everything being in order as above stated, 50 the proper coin is inserted in the slot of the coin controlled mechanism, thus starting the motor. The shafts 27 and 29 are rotated and the proper vat containing the character of polish desired is moved into position to be 55 engaged by the brushes by the movement of the lever 49 before mentioned. For convenience of description, each series of moving brushes will be designated by Roman numerals, the I series being the first series to engage the shoe after the brushes 32 which are 60 not movable. As the motor operates, the shaft 47 will be rotated, thus rotating the worm wheel 71, which by its engagement with the teeth 70 will cause the carriage to 65 move toward the seat. The brushes 32 will

first engage the sides and edges of the soles of the shoes, cleaning these parts of the shoes from dust and dirt. The brushes of series I supplement the action of the brushes 32, cleaning the tops and other portions of 70 the shoe from dust and dirt. The brushes of series II and III or of series IV and V as the case may be next engage the shoe, applying the polish, and the polish is dried by fans 72. Two fans are provided for each 75 shoe, and a current of air is blown onto each shoe from each side thereof. The shoes are last engaged by the brushes of series VI and VII, which are the finishing brushes, and complete the operation on the shoe. 80 When the carriage strikes the head of the lever 68, the said lever as also the teeth of series 70 are moved into the inclined position of Fig. 5, and the carriage may now move freely forward into its original position, 85 that is into position to again operate upon the shoes, merely by pulling the carriage forward, the teeth being now below the level of the worm wheel 71, so that they offer no resistance to the movement of the carriage. 90 When the carriage has been drawn out to the position of Fig. 1, it engages the lever 72^a, thus moving the teeth into the vertical position of Fig. 1, and into the proper position for engagement by the worm wheel, to 95 cause the carriage to move toward the seat when the motor is again put in operation.

It will be understood that the brushes of each series of the movable brushes will engage the shoes many times, while the carriage is moving the said brushes past the shoes, and they will engage the shoes at different points, thus thoroughly polishing the same. The latch mechanism for holding the lever 49 in adjusted position, is merely a cam 100 surface or projection, so that the lever may engage either end of the projection, to hold the lever in adjusted position. When not in use, the carriage could be pushed under the seat, into a position where it will be out of 110 the way and protected from injury.

I claim:

1. A machine of the character specified, comprising a base having a seat at one side provided with foot rests spaced apart from 115 each other, a carriage mounted for movement on the base toward and from the seat, a pair of upright standards on the carriage at each side of each foot rest, the members of each pair being spaced apart transversely 120 of the carriage, a pair of shafts journaled on each pair of standards and one above the other, a sleeve feathered on the lower shaft of each pair and movable longitudinally thereof, and near the center of the shaft, a 125 driving connection between each sleeve and the adjacent upper shaft, a fan on each upper shaft, a plurality of series of sprocket wheels on each shaft, one series being at one end of the shaft and the other series at the 130

other end, and the corresponding wheels of all of the shafts alining, an endless belt connecting the alining wheels of each pair of shafts, the sprocket wheels of the lower 5 shafts adjacent to the sleeve being loosely journaled on the shaft and the said wheels and the adjacent sleeve having co-acting means for connecting the wheels to the sleeve when the sleeve is moved toward the 10 wheels, a common means for moving all of the sleeves in either direction, and a series of polishing brushes connected to each belt, the connection between each brush and the belt being resilient, a plurality of tanks for holding 15 polishing material arranged longitudinally of the carriage below the sleeves, the tanks being beneath the loose wheels, and means operated by the sleeve moving means for raising the tank toward which the sleeve 20 is moved and for lowering the other tank, and a common means for rotating the shafts and for moving the carriage.

2. A machine of the character specified, comprising a base having a seat at one side 25 provided with foot rests spaced apart from each other, a carriage mounted for movement on the base toward and from the seat, a pair of upright standards on the carriage at each side of each foot rest, the members 30 of each pair being spaced apart transversely of the carriage, a pair of shafts journaled on each pair of standards and one above the other, a sleeve feathered on the lower shaft of each pair and movable longitudinally 35 of each pair thereof, and near the center of the shaft, a driving connection between each sleeve and the adjacent upper shaft, a plurality 40 of series of sprocket wheels on each shaft, one series being at one end of the shaft and the other series at the other end, and the corresponding wheels of all of the shafts alining, an endless belt connecting the alining wheels of each pair of shafts, the sprocket wheels of the lower shafts adjacent to the sleeve being loosely journaled 45 on the shaft and the said wheels and the adjacent sleeve having co-acting means for connecting the wheels to the sleeve when the sleeve is moved toward the wheels, a common means for moving all of the sleeves in either direction, a series of polishing brushes connected to each belt, and a common means for rotating the shafts and for moving the carriage.

2. A machine of the character specified, comprising a base having a seat at one side 25 provided with foot rests, a carriage movable toward and from the seat, and a series of polishing brushes mounted on the carriage at each side of each foot rest for engaging and polishing a shoe on the rest when the carriage is moved beneath the rests, means 30 for operating the brushes, sundry of the brushes of each series being loose on their shafts and adapted to apply polish of different character, a common means for connecting all of the brushes of either character to the operating means, means for supplying polish to each character of brushes, said means being operated by the means for connecting the brushes to the operating 35 means.

5. A machine of the character specified, comprising a base having a seat at one side provided with foot rests, a carriage mounted for movement on the base toward and from the seat, the base having guides at its ends 40 for guiding the carriage and having a groove in its upper face between the guides and parallel therewith, a series of teeth pivoted at their lower ends in the groove and spaced apart from each other, a link 45 connecting the teeth intermediate their ends, a worm wheel on the carriage for engaging the teeth, a plurality of series of polishing means supported on the carriage at each side of each rest, a common means for operating 50 the polishing means and for rotating the worm wheel, and a lever pivoted in the groove at each end of said link and extending above the groove and connected to the link, for engagement by the carriage at the 55

3. A machine of the character specified, comprising a base having a seat at one side provided with foot rests spaced apart from each other, a carriage mounted for movement on the base toward and from the seat, 60

end of its movement in opposite directions to move the teeth into and out of operative position.

6. A machine of the character specified, comprising a base having a seat at one side provided with foot rests, a carriage mounted for movement on the base toward and from the seat, the base having guides at its ends for guiding the carriage and having a 10 groove in its upper face between the guides and parallel therewith, a series of teeth pivoted at their lower ends in the groove and spaced apart from each other, a link connecting the teeth intermediate their ends, 15 a worm wheel on the carriage for engaging the teeth, a plurality of series of polishing means supported on the carriage at each side of each rest, a common means for operating the polishing means and for rotating the worm wheel, and means at each end of 20 the link and connected therewith for engagement by the carriage to move the teeth into and out of operative position.

7. A machine of the character specified, 25 comprising a base having a seat at one side provided with foot rests, a carriage mounted for movement on the base toward and from the seat, the base having guides at its ends for guiding the carriage and having a groove in its upper face between the guides and parallel therewith, a series of teeth pivoted at their lower ends in the groove and spaced apart from each other, a link connecting the teeth intermediate their ends, a 30 worm wheel on the carriage for engaging the teeth, a plurality of series of polishing means supported on the carriage at each side of each rest, a common means for operating the polishing means and for rotating the 35 worm wheel, and means operated by the carriage at the end of its travel in each direction for rocking the upper ends of the teeth into and out of the groove.

8. A machine of the character specified, 40 comprising a base having foot rests at one side, a carriage mounted for movement on the base toward and from the rest, polishing mechanism supported by the carriage adjacent to each rest for polishing a shoe on the 45 rest, a worm wheel on the carriage, a common means for driving the worm wheel and operating the polishing mechanism, and a series of teeth on the base for engagement by the worm wheel to move the carriage toward the seat, said teeth being mounted for 50 movement into and out of operative position, and means for engagement by the carriage at the end of its movement in each direction for moving the said teeth.

9. In a machine of the character specified, 55 a seat having a plurality of foot rests, a carriage movable toward and from the foot rests beneath the same, a plurality of series of belts supported for longitudinal movement on the carriage adjacent to each foot

rest, the series being on opposite sides of the rests, and the belts being supported for movement with one run vertical and adjacent to the rest, a common means for moving the belts and for moving the carriage, and 70 a series of brushes for each belt, a sectional arm connecting each brush with the belt, one section of each arm being secured to the brush and the other section to the belt, and a spring interposed between the sections. 75

10. In a machine of the character specified, a seat having a plurality of foot rests, a carriage movable toward and from the foot rests beneath the same, a plurality of 80 series of belts supported for longitudinal movement on the carriage adjacent to each foot rest, the series being on opposite sides of the rests, and the belts being supported for movement with one run vertical and adjacent to the rest, a common means for moving the belts and for moving the carriage, and 85 a series of brushes for each belt, and a resilient connection between each brush and the belt.

11. In a machine of the character specified, a seat having a plurality of foot rests, a carriage movable toward and from the foot rests beneath the same, a plurality of 90 series of belts supported for longitudinal movement on the carriage adjacent to each foot rest, the series being on opposite sides of the rests, and the belts having polishing means and being supported for movement with one run vertical and adjacent to the rest, and a common means for moving the 95 belts and for moving the carriage.

12. In a machine of the character specified, a pair of foot rests, a carriage movable beneath the rests, a series of cleaning brushes arranged on the carriage adjacent to each rest and at the rear of the carriage, a plurality of series of polish applying brushes mounted on the carriage adjacent to each rest for engaging the shoe immediately after the first-named brushes, a series 110 of finishing brushes, means for operating all of the brushes and for moving the carriage, and means operable at will for connecting any predetermined series of polishing brushes to the operating means and for 115 disconnecting the other, means adjacent to each series of polish applying brushes for supplying polish thereto, and a connection between the connecting means for the polish applying brushes and the supplying means 120 for moving the adjacent supply means into operative position when either series of polishing brushes is connected to the operating means.

13. In a machine of the character specified, a pair of foot rests, a carriage movable beneath the rests, a series of cleaning brushes arranged on the carriage adjacent to each rest and at the rear of the carriage, a plurality of series of polish applying 125

brushes mounted on the carriage adjacent to each rest for engaging the shoe immediately after the first-named brushes, a series of finishing brushes, means for operating all of the brushes and for moving the carriage, and means operable at will for connecting any predetermined series of polishing brushes to the operating means and for disconnecting the other.

14. In a machine of the character specified, a foot rest, a carriage movable toward and from the rest, a series of endless belts

mounted on the carriage on each side of the rest for movement with one run vertical and adjacent to the rest, a plurality of arms 15 connected to each belt and extending outwardly therefrom, a brush at the outer end of each arm, each arm being resilient, and means for moving the belts and the carriage.

FRANK V. MURPHY.
